SPECIFICATION forming part of Design No. 30,728, dated May 9, 1899.

Application filed April 4, 1899. Serial No. 711,739. Term of patent 7 years.

To all whom it may concern:

Be it known that I, JACOB F. HOKE, Jr., a citizen of the United States, residing at Sullivan, in the county of Sullivan and State of Indiana, have invented a new and original Design for Brush-Heads, of which the following is a specification.

My invention relates to a new and original design for brush-heads and is illustrated in the accompanying drawings, in which—

The leading feature of my design consists in a brush-head having a double-inclined bottom surface the parallel inclined faces of which are provided with parallel rows of holes containing a double row of tufts arranged parallel to each other, the free ends of which extend at an oblique angle from the sides of the said head.

In the said drawings the reference-numeral 1 indicates the brush-head, provided with a double-inclined bottom surface 2, the parallel inclined faces 3 4 of which are provided with 25 longitudinal parallel rows of holes 5 6, containing a double row of tufts 7 8, arranged parallel to each other, which tufts extend at an oblique angle to the sides of the brush-head 1, as shown at 9. The tufts at each end of 30 the brush-head extend at an oblique angle to the ends of the brush-head, and the top surface of the brush-head is provided with holes 10.

My design presents a brush-head of novel, 35 pleasing, and distinguishing appearance.

Having thus described my invention, what I claim is—

The design for a brush-head herein shown and described. 40

In testimony whereof I have hereunto set my hand in presence of two subscribing witnesses.
